UNITED STATES PATENT OFFICE

158,337

TELEVISION CABINET

Leland G. Stone, Fort Wayne, Ind., assignor to
The Magnavox Company, Fort Wayne, Ind., a
corporation of Delaware

Application April 27, 1949, Serial No. 2,288

Term of patent 7 years

(Cl. D56—4)

To all whom it may concern:

Be it known that I, Leland George Stone, a citizen of the United States, residing at Fort Wayne, in the county of Allen and State of Indiana, have invented a new, original, and ornamental Design for a Television Cabinet, of which the following is a specification, reference being had to the accompanying drawing, forming a part thereof.

In the drawing:

Figure 1 is a front perspective view of a television cabinet, showing my new design;

Figure 2 is a front perspective view similar to Figure 1 with the cabinet shown in open position; and

Figure 3 is a plan view.

I claim:

The ornamental design for a television cabinet, as shown.

LELAND GEO. STONE.
